UNITED STATES PATENT OFFICE.

CHRISTIAN MYLAND, OF PHILADELPHIA, PENNSYLVANIA.

DESIGN FOR A KNIFE AND FORK HOLDER.

40,746.

Specification for Design.

Patented June 28, 1910.

Application filed May 6, 1910. Serial No. 559,862. Term of patent 7 years.

To all whom it may concern:

Be it known that I, CHRISTIAN MYLAND, a citizen of the United States, residing at Philadelphia, in the county of Philadelphia and State of Pennsylvania, have invented a new, original, and ornamental Design for Knife and Fork Holders, of which the following is a specification, reference being had to the accompanying drawing, forming a part thereof.

The figure is a perspective view of a knife and fork holder, showing my new design.

I claim:

The ornamental design for a knife and fork holder, as shown.

CHRISTIAN MYLAND.
